UNITED STATES PATENT OFFICE.

WARREN S. HILL, OF BOSTON, MASSACHUSETTS.

ELECTRIC LAMP.

SPECIFICATION forming part of Letters Patent No. 248,465, dated October 18, 1881.
Application filed April 15, 1881. (No model.)

To all whom it may concern:

Be it known that I, WARREN S. HILL, of Boston, county of Suffolk, and State of Massachusetts, have invented certain new and useful Improvements in Electric Lamps, which improvements are fully set forth in the following specification.

My invention relates to certain improvements in electric lamps, and has special reference to a lamp in which two sets of carbons are employed, arranged so that when one set of carbons have been consumed the remaining set shall be automatically or without manual intervention brought into use, thus admitting of a continuous light being maintained for a longer time than it could be by the use of only one set of carbons.

It is my object in a lamp of this kind to provide a simple and effective mechanism whereby, while one set of carbons are being consumed the other set shall be kept out of the electric circuit, and be otherwise entirely inoperative until such time as the first set are burned as low as is desired, at which time the circuit between the burning carbons shall be broken, the second set of carbons are brought together, the electric arc formed at their points, and the light instantaneously transferred to the new set of carbons. This result I accomplish by means of a tilting bar or lever pivoted at a point between the feed-rods, and arranged so that it is held at one of its extreme points of motion by the action of a spring, and when forced to the other extreme of its motion is caught and held by a catch or sear. While the bar is in the latter position the points of the first set of carbons are together, and their respective feed-rod is in operative connection with a regulating apparatus, while the upper carbon of the second set is held suspended above and out of contact with its co-operating carbon. Thus the circuit is completed, and the electric arc formed at the points of the first set only. Feed-rod No. 1 is provided with a collar, placed at such a point that when the carbons are burned nearly to their sockets the collar will strike a projecting arm of the sear, causing it to release its hold of the tilting bar, when the action of the spring causes it to resume its normal position, and by means of a

pin bearing against the under side of the collar to raise the feed-rod and upper carbon of set No. 1, separating their points and breaking the electric circuit. At the same time it releases feed-rod No. 2 and allows its suspended carbon to fall and meet with its co-operating carbon, thus completing the circuit through the new set of carbons, and the light is established at the meeting-points of set No. 2 simultaneously with its extinction at the points of set No. 1, and a continuous light is maintained without perceptible break or interruption.

My improvement may be successfully employed in combination with different styles of regulating mechanism. I therefore do not limit myself to its use in connection with any particular style of regulating apparatus.

The accompanying drawings are an illustration of my invention as applied to the regulating mechanism employed in the lamp invented by Edward Weston.

Figure 1 shows the lamp in elevation, with the electro-magnets removed. Fig. 2 is a section on line *xx* in Fig. 1, and is enlarged. Fig. 3 is a sectional plan view on line *yy* in Fig. 2. Fig. 4 is a rear view of the locking device, the position of the lever when changed and its relation to the feed-rod and collar being shown in dotted lines. Fig. 5 is a section through the center of the lower carbon-holder, Fig. 6 being a perspective of the spring-sleeve within the holder.

In Fig. 1 is shown the frame or body of the lamp, consisting of the plates *a* and *b*, united at a suitable distance apart by the side rods, *A A*.

To the top plate, *a*, are secured the different parts that go to make up the automatic regulating mechanism that operates and controls the feeding of the upper carbon, while to the lower plate, *b*, are secured the lower carbon-holders, as shown at *e e*.

Referring to Figs. 2 and 3, the electro-magnets *M M* are secured to the plate *a* by means of the support *j*, and the armature *l*, with its connecting parts, is secured in like manner by the support *k*, with the regulating-spring, dashpot, and gripe shown, all of which constitute the main features of the regulating mechani-

ism of the ordinary "Weston" lamp, the operation of which is thus briefly described: The electric current, entering the lamp at one of the binding-posts, passes through the wire on the electro-magnets to the plate; thence down the feed-rod through the upper and lower carbons, to the lower plate, up one of the side rods to the opposite binding-post and out, proper insulation being employed to direct its course. In its passage through the magnets, their iron cores are charged with magnetism, which, acting on the armature, draws it upward, lifting the feed-rod and the upper carbon by means of the gripe, which is secured to the armature, grasping the rod, thus separating the carbons and making the light at their points in the manner well understood.

In my improved lamp I provide two feed-rod supports, which are shown at $g' g'$, and are secured to the plate a , one at either side of the armature l . At the top of these supports is a cross-piece with an arm projecting upward, to which is pivoted at n the tilting bar m . A spiral spring, s , surrounds its axis and operates to tilt the bar to the position shown in the dotted lines.

At the lower end of the armature l are two studs, $w w'$, which engage the ends of the gripe-levers $L L'$. These gripes embrace the feed-rods loosely, so that when they lie in a horizontal position the rod moves freely through the opening therein; but when the end of the gripe is raised, placing it at a slight angle, the rod is grasped by the sides of the hole impinging against the rod, and it is raised or held suspended so long as the gripe is held clear of the plate a .

It will be seen that the gripe does not fill the space between the armature and the head of the stud w , but has free play perpendicularly.

To the inner end of gripe L is secured a chain, w' , by which it is connected with the short arm of the bar m . When the bar m is in the position shown in Fig. 1 the gripe L is raised clear of the plate a , and, being suspended by the short end, will, by its gripe on the feed-rod h , hold it with its carbon suspended at any point desired, as shown; and as the perpendicular play of the gripe on the stud w is greater than the movement of the armature l in its ordinary working, the feed-rod h , while in this position, is unaffected by the movement of the armature, and is entirely inoperative. While the feed-rod h is thus suspended the gripe L' rests on the head of the stud w' , and as the armature l is raised by the magnetic attraction of the magnets $M M$ the gripe L' is raised, taking up with it the feed-rod h' , separating the carbons, and producing the electric arc at the points of the carbons $c' d'$. Thus while the parts are in this position the operation of the feed-rod h' , with its co-operating parts, are in all respects the same as in the ordinary lamp having but a single set of carbons.

It will be seen that the long arm of the bar

m is drawn down against the tension of the spring s , and is held down by the plate r engaging with the hook o of the sear N , (see Fig. 4,) the spring v , under the arm p of the sear, making it self-locking as it enters the hook o . q is a pin projecting from the bar m toward the feed-rod h' .

i is a collar secured to the rod h' by a set-screw, and may be placed so that when the carbons $c' d'$ have burned nearly to their holders it will bear on the arm p of the sear and cause it to release its hold of the plate r , when the tension of the spring s will cause the bar m to change its position to that shown in the dotted lines. As the long arm of the bar m is raised the pin q , bearing against the under side of the collar i , raises the rod h' , separating the carbons $c' d'$, thereby breaking the circuit between their points and extinguishing the light.

The rod u , attached to the bar m , as shown in Fig. 3, has an offset projecting under the gripe L' , and, as the long end of the bar m is raised, lifts the gripe L' to the position shown in the dotted lines, where, by reason of the perpendicular play on stud w' , it is unaffected by the movement of the armature l , and it, together with the feed-rod h' , is rendered inoperative. The tilting of the bar m has allowed the gripe L to fall until the regulating screw D , resting on the plate a , causes it to release its gripe on the feed-rod h , allowing the latter to fall until its carbon c rests on its co-operating carbon d , thereby completing the electric circuit through the new set of carbons $c' d'$ simultaneously with the circuit being broken between the points of the consumed carbons $c' d'$; and as the feed-rod h is now brought into action by the operation of the armature l , the light is continued at the meeting-points of the new set of carbons without interruption, as would be necessary were only one set employed.

It will be seen that while feed-rod h is in operation the gripe L rests on the head of stud w and is put in operative motion by the movement of the armature l , the same as feed-rod h' before the bar m had changed position, and also the same as the feed-rod working in an ordinary lamp. Thus while either feed-rod, with its respective carbon, is in operation the other feed-rod and its carbon are held, without weight or labor to the regulating mechanism, entirely inoperative.

The pendent rod t is secured to the long end of bar m and extends through the plate a , terminating in a ring or eye.

When the lamp is in use the mechanism above the plate a is covered with a suitable case, and to put it in operation, a stick of carbon is placed in each of the upper and lower holders, when, by drawing down the rod t , the long end of the bar m is brought down and locked. The feed-rod h is now raised enough to prevent any current passing between the points of carbons c and d , and the lamp is ready for operation. Upon receiving the proper current of electricity the

feed-rod h' will be put in operation by the action of the armature l with its accompanying mechanism in the manner heretofore described, and the light will be produced at the points of 5 carbons $c' d'$, and will continue until they are consumed nearly to their holders when the collar i will strike the arm p of the sear N , causing it to release its hold of the bar m , whereupon the feed-rod h' is thrown out of operation 10 and feed-rod h brought into action, as has been described, both changes occurring at the same instant, thus transferring the light to the new set of carbons with scarcely a perceptible interruption.

15 In case these lamps are employed where it is desired to maintain a light for a continuous period throughout the twenty-four hours of the day, as in mines or tunnels, the exhausted carbons may be replaced by new ones at any 20 time after the transfer has taken place, when, by drawing down the rod t and at the same time raising carbon c , the light will be retransferred back to the first set of carbons. In this way the second set may be held as a reserve 25 to use while the first set are being replenished, and a continuous light may be kept up for an indefinite time. A workman skilled in the care of electric lamps will have no difficulty in trimming the lamp while it is in operation.

30 To facilitate the adjustment of the gripe-levers $L L'$, so that each lever may be made to release its hold of the feed-rod at the same point of elevation of the armature, I have provided the adjustment-screws $D D'$, whereby 35 the releasing-point of the gripe-levers may be adjusted to perfect accuracy, and inasmuch as the adjustment may be effected while the lamp is in operation there is no difficulty in obtaining the required breadth of arc when either 40 set of carbons are in operation.

In Figs. 5 and 6 is shown the construction of the carbon-holders. The bottom holders are made detachable, and are held in place by projecting flanges, parts of which pass under lugs 45 or ears secured to the plate b , and as any one of many different ways may be employed to hold them in place these parts are not shown in the drawings. The upright column of the holder e has a hole through its center of a size to receive 50 a carbon. At its upper end the hole is enlarged to receive the slotted sleeve E . This sleeve is divided at its ends into a number of divisions, as shown, and when placed within the holder e and the nut e' is screwed down 55 its beveled inner surface bears against the points c^2 , closing them together, and a carbon placed within the holder will be grasped and securely held in place, and by grasping the carbon on all its sides but little pressure will 60 be required to hold it securely, and there will be less danger of breaking the carbons than when they are held by a set-screw bearing on one side only. The lower end of the sleeve E may have a part on all its points converging 65 slightly to the center, just enough to grasp the carbon loosely, so that it will not slip through

of its own weight, and thereby hold the carbon from falling when the nut e' is loosened. The upper holders are provided with a similar device.

I am aware of the use of electric lamps wherein two sets of carbons are arranged so that when the electric circuit has been made through both pairs the contact between one pair of carbons is broken in advance of the other, producing the light at the points of the pair last separated, both sets of carbons being in mechanical operation at the same time, and the separation of the points of the idle pair being but slightly in excess of that of the working 70 pair. Under my invention, however, the idle carbon is held motionless at a considerable distance from its co-operating carbon, there being a break or interruption mechanically effected at some point in the mechanism which 75 transmits movement from the armature to said idle carbon, whereby the latter is uninfluenced and unaffected by the armature and receives no motion therefrom; and this result I accomplish by combining with the sets of carbons 80 and the regulating armature feed mechanisms, one for each set of carbons, a spring or equivalently-controlled feed-shifter, of which bar m is one convenient form, connected with each of said feed mechanisms in such manner 85 that when the armature is in operative connection with one feed mechanism it will be out of operative connection with the other, and a detent which operates to hold the feed-shifting device in one of its two positions, and is 90 actuated at the proper time from or by the moving feed-rod of the set of carbons operative in that position to release said feed-shifting device, which then automatically shifts to its 95 other position, so as to bring into action the 100 other set of carbons and their feed mechanism, and to throw out of action the first set of carbons, together with their feed mechanism.

What I claim as new, and desire to secure by Letters Patent, is—

1. In an electric lamp containing two sets of carbons, the combination, with feed mechanisms, one for each set of carbons, of a tilting spring or equivalently-controlled feed-shifting bar connected with each of said feed mechanisms, and a catch or detent which engages the said bar and is operated to release the same at the time and in the manner substantially as specified, the combination being and acting substantially as hereinbefore set forth.

2. The combination, with the independent carbon-feed mechanisms, of the bar-holding detent operated by or from the moving feed-rod of the set of carbons in action, and the spring or equivalently-controlled tilting feed-shifting bar connected with said feed mechanisms, and formed and arranged to engage and lift, when released from control of the detent, the feed-rod by which its release was effected, substantially as hereinbefore set forth.

3. The combination of the gripe-levers, the carbon feed rods, the vibratory spring or equiv-

4. A lenily-actuated feed-shifting bar connected with said gripe-levers, and the detent or sear, these elements being combined and having the mode of operation substantially as hereinbefore set forth.

5. In an electric lamp, and in combination with the bar *m* and the collar *i*, the sear *N*, having hook *o* and arm *p*, with spring *v*, arranged and operating to hold said bar at one extreme 10 of its motion, or to release the same at a point determined by the position of the collar *i* on the rod *h'*, substantially as shown, and for the purpose specified.

6. In an electric lamp, the pin *q*, connected 15 to the spring-actuated bar *m*, and operating, in combination with the collar *i*, to raise and hold suspended the feed-rod *h'* while the feed-rod *h* is in operative connection with the armature, substantially as shown and for the purpose 20 specified.

7. The combination, with the feed actuating

or regulating armature and the carbon-feed rods, of the gripe-levers, and the adjusting-screws carried by the same, arranged and operating substantially as and for the purposes 25 hereinbefore set forth.

8. The combination, substantially as hereinbefore set forth, in an electric lamp, of the vibratory spring-actuated bar or lever, the bar-holding detent, the carbon-feed rod, operating 30 to disengage the detent from the bar at the time and in the manner substantially as specified, and the handle whereby said bar may be moved against the stress of its spring so as to re-engage the detent.

In testimony whereof I have signed my name in the presence of two subscribing witnesses.

WARREN S. HILL.
